UNITED STATES PATENT OFFICE

HENRY B. LANDAU, OF SANDUSKY, OHIO, ASSIGNOR TO GENERAL CHEMICAL COMPANY,
OF NEW YORK, N. Y., A CORPORATION OF NEW YORK

BAG MACHINE

Application filed June 7, 1924. Serial No. 718,458.

In existing commercial life many commodities are advantageously stored and transported in bags of jute or similar material; because of the character of the merchandise it is 5 desirable in many cases to provide such bags with liners of paper or other suitable material.

The present invention relates to this type of bags and has for its object to provide a 10 simple apparatus whereby the bag liners of paper or other suitable material may be combined with the bags of jute or other material in a rapid and efficient manner and with the possibility of tearing or otherwise mutilating 15 the liner reduced to a minimum.

The invention contemplates further the provision of means whereby stenciling of the bags or the application of other marks there-to is facilitated. Other objects will appear 20 from the description hereinafter and the features of novelty will be pointed out in the appended claims.

In the accompanying drawing, which illustrates an example of the invention without 25 defining its limits, Fig. 1 is a perspective view of the machine and Fig. 2 is a side elevation thereof.

As shown in the drawing the apparatus consists of a suitable support 10, which may 30 be in the form of a bench or table, and a carrier 11; the latter may be in the nature of a rectangular frame of any suitable material such as metal rods, bars or pipes and is pivotally connected at 12 with suitable pivot blocks 35 or the like 13 fixed upon the horizontal bed or supporting surface 14 of the support 10 near one end thereof. At its free end *a* the carrier 11 is provided with light tension springs 15 located upon opposite sides thereof 40 and constructed and arranged to exert tension in outward directions for the purpose to be more fully set forth hereinafter. A counter-weight 16 is mounted upon the carrier 11 in a manner to counterbalance the same and 45 is located in contiguous relation to a stop 17 projecting upwardly from the bed 14; the stop 17 is of such dimensions and arrangement as to permit the free end *a* of the carrier 11 to be swung to a predetermined extent 50 in a direction away from the bed 14 within

the lateral limits defined by the sides of the bed, or in other words to allow an up and down motion sufficient to permit a bag to be readily combined with the carrier as will appear more fully hereinafter. In the normal 55 condition of the parts, the free end *a* of the carrier 11 rests upon a stop 18 secured upon the bed 14 as shown in Fig. 1. A second carrier 19 which may be a duplicate of the carrier 11 and likewise comprise a rectangular 60 frame of suitable metal, is pivotally connected at 20 with pivot blocks 21 mounted upon the bed 14; the carrier 19 does not require tension springs such as the springs 15. The second carrier 19 is also provided with 65 a counter-weight 22 which is so located and arranged as to permit the carrier 19 to be swung on its pivots 20 through an arc of one hundred and eighty degrees. The arrangement of mounting the carriers is such that the 70 carrier 19 may be swung to a position in which it projects toward the carrier 11 and has its free end *b* resting upon the stop 18 in close proximity to the free end *a* of said carrier 11 as shown in Fig. 1. The path and direction of movement of these carriers 11 and 19 in relation to the bed 14 is so governed by 75 the mounting constructions that the arc described by any point on the moving carriers will lie within the lateral limits defined by 80 the sides of the bed and in a plane perpendicular to the plane of the surface of the bed. It will be understood that the carriers 11 and 19 are pivoted at the same height so as to be located at a common level when projecting toward each other as in Fig. 1 and that said carriers are somewhat longer than the length 85 of the bags to be accommodated and somewhat less in width than the width of said bags.

In addition to the parts so far described the 90 apparatus includes a stop 23 located upon the bed 14 of the support in a position to provide a rest for the end *b* of the second carrier 19 when the latter is swung to the position shown by dotted lines in Fig. 2. At a point 95 upon the bed 14 between the stop 23 and the pivot blocks 21 a stencil block 24 may be provided to permit the bag to be stencilled upon one side before it is removed from the apparatus. Suitable means may be included for 100

also stencilling or otherwise marking the other side of the bag if this should be desired. The stencilling may be accomplished by means of any suitable stencilling device and if desired may include means whereby ink is sprayed by compressed air through a stencil from below.

In practice a supply of jute or other bags is placed upon the bed or in any other convenient location with their open ends projecting toward the carrier 11 and a supply of empty bag liners is likewise placed in position within convenient reach of that end of the support 10 at which the stop 23 is located. The apparatus is preferably manned by two operators one of whom stands at the support 10 near the stencil block 24 and the other of whom stands at the opposite side of the support at a point about in registry with the stop 18. The latter operator raises the carrier 11 and draws a jute bag over the same, the closed end of said bag being interiorly clamped by springs 15, and then restores the carrier, with the jute bag in place thereon, to the position shown in Fig. 1. While these operations are being performed by the one operator, the other places a bag liner upon the second carrier 19, which at this stage occupies the position indicated by dotted lines in Fig. 2, and then swings the carrier 19, with the liner thereon to the position shown by solid lines in Fig. 1. With the parts in this adjustment the closed ends of the jute bag upon the carrier 11 and the bag liner upon the carrier are in close proximity to and project toward each other. The first operator thereupon grasps the jute bag upon opposite sides at its open end and pulls the bag upon itself or in other words turns it inside out upon the carrier 11 and finally draws said bag over the liner upon the carrier 19. This operation is easily carried out by reason of the fact that the carriers position the bag and liner at the same level and in exact alignment with each other as shown in Fig. 1. When the jute bag has been fully pulled over the liner and thereby combined the two, the carrier 19 is swung back to the position indicated by dotted lines in Fig. 2 in which the outer end rests upon the stop 23 and the stencil block 24 is beneath and in engagement with the bag at an intermediate point. If desired, a suitable stencil may accordingly be applied, for instance, as hereinbefore set forth, after which the second operator, by gripping the bag at its bottom, pulls the lined bag from the carrier 19 and places it on a truck or stock-pile or otherwise disposes of it.

A new bag is meanwhile being placed upon the carrier 11 and a new liner drawn upon the carrier 19 and the same cycle of operations is repeated in sequence. During the transfer of the bag from the carrier 11 to the carrier 19 the closed end of said bag is held by the springs 15 so that turning said bag in-

side out and placing over the liner is accomplished without difficulty. If desired, provision may be made for applying a stencil or other mark to the bag directly after it has been drawn over on the liner upon the carrier 19 so that said bag may be stencilled or marked in two places.

The invention provides a simple and efficient apparatus for quickly and easily lining bags which requires no skilled supervision and is easily operated by unskilled labor.

Various changes in the specific form shown and described may be made within the scope of the claims without departing from the spirit of my invention.

I claim:

1. An apparatus for lining bags comprising cooperating complemental carriers arranged and constructed to carry a bag and a liner respectively, each carrier being pivoted to move independently in a vertical plane into cooperative relation with the other.

2. An apparatus for lining bags comprising a support, a carrier for a bag pivotally mounted upon said support for movement in a vertical plane, and a second carrier for a liner pivotally mounted upon said support for movement in a vertical plane through an arc of 180°, said second carrier being adapted to move into aligning registry with said first carrier and bag to permit the latter to be turned inside out and stripped from said first carrier and drawn over said liner on the second carrier.

3. An apparatus for lining bags comprising a support, a carrier pivotally mounted upon said support for carrying a bag and a second carrier pivotally mounted upon said support for carrying a liner and movable into opposed conterminous relation to said first carrier and bag to permit the latter to be turned inside out and stripped from said first carrier and drawn over the liner on said second carrier and counterweights on each of said carriers for counterbalancing the same.

4. An apparatus for lining bags comprising a support, a stencil block thereon, a carrier pivotally mounted upon said support for carrying a bag, and a second carrier pivotally mounted upon said support for carrying a liner into aligning registry with said first carrier and bag to permit the latter to be turned inside out and stripped from said first carrier and drawn over said liner on the second carrier, the latter being movable through an arc of 180° to bring the combined bag and liner over said stencil block and a stop constituting a rest for the free end of said second carrier to position said bag and liner over said stencil block.

5. An apparatus for lining bags comprising a support, a carrier pivotally mounted upon said support for carrying a bag and a second carrier pivotally mounted upon said

support for carrying a liner and movable into opposed conterminous relation to said first carrier and bag to permit the latter to be turned inside out and stripped from said first carrier and drawn over the liner on said second carrier, a stop constituting a rest for the opposed ends of said frames and counterweights for counterbalancing said carriers.

5. An apparatus for lining bags comprising a support, a carrier pivotally mounted upon said support for carrying a bag, and a second carrier pivotally mounted upon said support for carrying a liner and movable into opposed conterminous relation to said first carrier and bag to permit the latter to be turned inside out and stripped from said first carrier and drawn over the liner on said second carrier, the latter being pivotally movable away from said first carrier through 10 an arc of one hundred and eighty degrees to permit removal of the lined bag, a stop constituting a rest for the free end of said second carrier in said last named position, a stop constituting a rest for the opposed ends of 15 said carriers when in opposed relation and a counterweight on each of said carriers for counterbalancing the same.

6. An apparatus for lining bags comprising a supporting surface, co-operating complementary carriers mounted on said surface and arranged and constructed to carry a bag and a liner respectively, each carrier being pivoted to move independently in a path perpendicular to the supporting surface.

35. 8. An apparatus for lining bags comprising a supporting surface, co-operating complementary carriers mounted on said surface and arranged and constructed to carry a bag and a liner respectively, each carrier being pivoted to move independently into and out 40 of co-operative relation with the other in a common plane perpendicular to the plane of said supporting surface.

9. An apparatus for lining bags comprising a supporting surface, a carrier for a bag pivotally mounted upon said supporting surface for movement in a path wherein the arc described by any point on the moving carrier will lie in a plane perpendicular to 45 the plane of said surface, and a second carrier for a liner pivotally mounted upon said surface for movement through an arc of 180° in a path wherein the arc described by any point on the moving carrier will lie in a plane 50 perpendicular to the plane of said surface, said second carrier being adapted to move into aligning registry with said first carrier and bag to permit the latter to be turned inside out and stripped from said first carrier and drawn over said liner on the second carrier.

In testimony whereof I have hereunto set my hand.

HENRY B. LANDAU.
